DESIGN FOR A ROTATABLE VENTILATOR

Herman D. Murray, Marshall, Mich., assignor to
Woodlin Metal Products Company, Marshall,
Mich., a firm owned and operated by Walter J.
Woodhams and Alfred Laughlin as copartners

Application July 17, 1942, Serial No. 107,590

Term of patent 7 years

To all whom it may concern:

Be it known that I, Herman D. Murray, a citizen of the United States, residing at Marshall, in the county of Calhoun and State of Michigan, have invented a new, original, and ornamental Design for a Rotatable Ventilator, of which the following is a specification, reference being had to the accompanying drawing, forming part thereof.

Figure 1 is a perspective view of a rotatable ventilator embodying my new design.

Figure 2 is a perspective view of the rotatable ventilator shown in Figure 1, but taken from the opposite side.

I claim:

The ornamental design for a rotatable ventilator, substantially as shown.

HERMAN D. MURRAY.
